VENTILATOR

William A. Norris, Alhambra, Calif.

Application July 1, 1942, Serial No. 449,209

4 Claims. (Cl. 98-43)

This invention relates to ventilators.

The general object of the invention is to provide an improved ventilator which is particularly adapted for use in drawing air from the upper portion of a room such as the kitchen and for forcing the air into the garret.

A more specific object of the invention is to provide a fan operated ventilator with a housing thereabout and wherein novel means is provided for closing the air passage from the housing.

A further object of the invention is to provide a novel mounting for the parts of a ventilator.

An additional object of the invention is to provide a novel floating closure member for closing the outlet portion of a ventilator housing.

Other objects and advantages of the invention will be apparent from the following description taken in connection with the accompanying drawing wherein:

Fig. 1 is a central sectional view through a ventilator embodying the features of my invention;

Fig. 2 is a top plan view of the ventilator with parts broken away;

Fig. 3 is a side elevation of the ventilator;

Fig. 4 is a top plan view showing the motor support;

Fig. 5 is a side elevation, on a reduced scale, showing the ventilator with the conduit thereon;

Fig. 6 is a side elevation, with parts broken away, showing a modification; and

Fig. 7 is an enlarged sectional detail showing the modification.

Referring to the drawing by reference characters I have shown my invention as embodied in a ventilator which is indicated generally at 10. As shown the ventilator includes a cylindrical housing 11 which may be made of sheet metal.

The housing includes a plurality of foot members 12 which are shown as arranged in diametrically opposed pairs. The foot members are arranged within the housing and are secured thereto as by welding at 13. Each foot member includes an outwardly directed, radially extended portion 14 through which fastening members such as screws 15 extend to secure the housing to the ceiling 16 of a dwelling. A pair of the opposed foot members have inwardly directed portions thereon as at 17 which extend into the housing and engage a support 18 to which they are removably secured by screws 19.

The support includes a generally circular body portion 20 and outwardly extending finger portions 21. The portions 20 and 21 are provided with a continuous peripheral downwardly extend-

ing flange 22. The portion of the flange 22 about the circular portion 20 is of a size to engage the top portion 23 of a motor 24 which is secured to the circular portion 20 by bolts 25.

5 The motor 24 includes an armature shaft 27 on which an air impeller 28 is mounted. This air impeller includes a hub portion 29 and a plurality of blades 30. Each blade includes an inclined portion 31 by means of which air is forced upwardly in the housing 11. An impeller of similar construction is shown in my prior Patent 2,271,709, granted February 3, 1942.

To operate the motor the latter is provided with a conductor member 32 which terminates in a plug 33. The plug 33 fits into a receptacle 34 from which wires 35 extend to a suitable source of power.

20 The blades 30 are so proportioned and spaced that when the screws 19 are removed the entire motor assembly with the air impeller thereon may be moved downwardly in the housing so that a pair of the blades straddle the receptacle 34. To remove the motor the plug 33 is pulled from the receptacle 34 and the screws 19 are released.

25 Above the impeller 28 the housing is provided with an inwardly directed bead 36 which, when the motor is not running, is engaged by a closure member 37. This closure member comprises a disc having a peripheral bead 38 and having stiffening ribs 39 which intersect a central circular bead 40. The construction of the beads 36 and 38 is such that an insect and dust tight seal is provided where the beads engage.

30 The disc 37 is made of light weight material such as aluminum, plastic, etc., and when the motor is operated by closing a switch (which controls flow of current through the leads 35) the impeller 28 draws air through a closure member 41 at the lower portion of the housing and the column of air striking the closure 37 lifts the closure upwardly to the dotted line position in Fig. 1 where the closure engages stop members 42 to limit the upward movement of the closure.

35 The housing is provided with openings 43 which are arranged above the bead 36 and beneath the stop members 42. The air advanced by the impeller 28 passes outwardly through the openings 43.

40 The closure 41 includes an annular rib portion 44 held in place by the screws 15 and a central portion 45 which is made of suitable mesh material.

45 In order to conduct air which passes through the opening 43 to a remote location I show the

housing 11 as provided with a conduit member 46. This member includes a lower portion 47 which has a tight sliding fit with the housing 11 and a conduit portion 48 connected to the portion 47 by a flaring portion 49.

In Figs. 6 and 7, I show a modification of my invention wherein the housing, motor mounting, and associated parts are similar in all respects to that described above. In the modification the armature shaft 27' extends upwardly into the housing. A disc member 50, similar to the disc member 39 previously described, includes a depending tubular member 51 which has a flaring lower end 52 and a flange 53 at the upper end. A member 54 is arranged opposite the flange 53 and the parts are secured together by bolts 55.

The members 50, 51 and 54 have a central aperture 56 which receives the upper end of the armature shaft 27'. When the motor is not running the disc closure member 50 takes the position shown in dotted lines shown in Fig. 6. When the motor is running the column of air lifts the disc member 50 to the solid line position shown in Fig. 6. In this latter position the flaring skirt 52 is free from engagement with the armature shaft 27' so that there is no wear on the parts.

From the foregoing description it will be apparent that I have invented a novel ventilator which can be economically manufactured and is highly efficient for its intended purpose.

Having thus described my invention, I claim:

1. In a ventilator, a cylindrical housing having a plurality of foot members thereon, said foot members having outwardly directed radially extending portions adapted to engage a portion of a wall, a closure member including a reticulated central portion and a peripheral collar secured thereto, means to secure said collar to said radially extending portions on certain of the foot members, a receptacle outlet member mounted in said housing, certain of said foot members being opposed and having inwardly extending portions thereon, a support removably mounted on said inwardly extending portions, said support extending across said housing, a motor removably mounted on said support, said motor having a plug member thereon adapted to fit said receptacle, said motor having an armature shaft, an air impeller mounted on said shaft, said impeller including radial blades, the blades adjacent their free ends being spaced apart a distance greater than the width of said receptacle whereby the blades may pass the receptacle when the motor is free, said housing extending beyond the impeller and including a plurality of spaced outlets in the sidewall thereof, said housing having a bead adjacent to the inner portion of said outlets, a freely floating plate closure member engaging said bead, said plate member being slideable in said housing, and comprising a disc including stiffening ribs and a peripheral flange and means on said casing and at the edge of said outlets remote from said casing bead to limit the outward movement of said disc.

2. In a ventilator, a cylindrical housing, a support mounted in said housing, a motor mounted on said support, said motor having an armature shaft, an air impeller mounted on said shaft, said impeller including radial blades, said housing extending beyond the impeller and including a plurality of spaced outlets in the sidewall thereof, a plate member slideable on said shaft and when in upper position being free from engagement with said shaft, and means to limit the outward movement of said disc.
3. In a ventilator, a cylindrical housing having a plurality of foot members thereon, said foot members having outwardly directed radially extending portions adapted to engage a portion of a wall, certain of said foot members being opposed and having inwardly extending portions thereon, a support removably mounted on said inwardly extending portions, said support extending across said housing, a motor mounted on said support, said motor having an armature shaft, an air impeller on said shaft, said impeller including radial blades, said housing extending beyond the impeller and including a plurality of spaced outlets in the sidewall thereof, said housing having a bead adjacent to the inner portion of said outlets, a plate closure member slideable on said armature shaft, said plate closure member engaging said bead, said plate closure member comprising a disc including stiffening ribs and a peripheral flange and means on said housing at the edge of said outlets remote from said housing bead to limit the outward movement of said disc.
4. In a ventilator, a cylindrical housing having a plurality of foot members thereon, said foot members having outwardly directed radially extending portions adapted to engage a portion of a wall, certain of said foot members being opposed and having inwardly extending portions thereon, a support removably mounted on said inwardly extending portions, said support extending across said housing, a motor mounted on said support, said motor having an armature shaft, an air impeller on said shaft, said impeller including radial blades, said housing extending beyond the impeller and including a plurality of spaced outlets in the side wall of the extending portion, said housing being imperforate below the spaced outlets, said air impeller being located below said spaced outlets, said housing having a bead adjacent to the inner portion of said outlets, a freely floating disc closure having a diameter less than the inner diameter of said housing, said closure engaging said bead, said disc closure including stiffening ribs and a peripheral flange and means on said housing at the edge of said outlets remote from said housing bead to limit the outward movement of said disc closure, said disc closure being disposed above said impeller so that it is raised by the column of air from said impeller, said disc closure being free to drop by gravity when the impeller is idle.

WILLIAM A. NORRIS.
